DESIGN FOR A KNIFE BOX

Augustine M. Mazzarelli, New York, N. Y.

Application January 16, 1945, Serial No. 117,457

Term of patent 14 years

(Cl. D44—29)

To all whom it may concern:

Be it known that I, Augustine M. Mazzarelli, a citizen of the United States, residing in the Borough and county of Queens, in the city and State of New York, have invented a new, original, and ornamental Design for a Knife Box, of which the following is a specification, reference being had to the accompanying drawing, forming part thereof.

On the drawing,

Fig. 1 is a front elevational view of a knife box embodying my design;

Fig. 2 is a top plan view of the knife box shown in Fig. 1;

Fig. 3 is a side elevational view of the knife box shown in Fig. 1; and

Fig. 4 is a transverse cross-sectional view, substantially on the line 4—4 of Fig. 1.

I claim:

The ornamental design for a knife box, as shown.

AUGUSTINE M. MAZZARELLI.
